SOOT CLEANER FOR STOVEPIPE DRUM OVENS

George H. Swearingen, Louisville, Ky., assignor
to Louisville Tin and Stove Company, Incorporated, Louisville, Ky.

Application January 31, 1938, Serial No. 187,957

2 Claims. (Cl. 126—17)

This invention relates to soot cleaners for stove pipe drum ovens, and the principal object of the invention is to provide simple, reliable, efficient and inexpensive means for removing soot deposits from such ovens.

A further object of the invention is to provide a drum and soot cleaner construction whereby certain advantages in the use of such drums and cleaners are obtained, as hereinafter fully described.

In the accompanying drawing illustrating the invention—

Fig. 1 is a side elevation, with parts broken away and in section, of a pipe oven with a soot cleaner embodying the invention.

Fig. 2 is a vertical transverse section on line 2—2 of Fig. 1.

Fig. 3 is a detail section through one end of the drum showing the operating crank and its mounting.

Fig. 4 is a view of the cleaner per se detached from the oven.

Referring now more particularly to the drawing, 1 designates a stove pipe oven which is constructed, as usual, with spaced inner and outer annular walls 2 and 3, respectively, said walls having the form of cylinders providing an annular heat chamber 4 for the passage of the smoke and products of combustion through the oven. The oven is provided with an inlet 5 and an outlet 6 communicating with said chamber 4 and which in practice connect the oven with sections of a stove pipe leading from a stove to a chimney or flue.

The inner cylinder or wall 2 encloses an oven chamber 7 which is provided at the front of the oven with a door 8 giving access thereto. The rear end of the oven chamber 7 is closed by a wall 9, connected with the cylinder 2, while the rear end of the oven body is closed by a wall 10 connected with the cylinder 3.

The door 8 closes an opening formed in an end wall 8a and forming the entrance to the oven chamber 7. This wall 8a forms the front wall of the casing to which the forward end of the oven chamber 7 is attached and by which said end of the oven chamber is supported. In ovens of this type it is necessary to provide some suitable fastening or supporting means in addition to the fastening connection between the oven chamber 7 and the front wall 8a to sustain and prevent said oven chamber from sagging under its weight plus the weight of its contents and causing buckling or dishing of the front wall 8a, as well as to pre-

vent the walls of said chamber from being unduly warped or buckling under the intense heat. As the use of such fastening or supporting means extending across the channel 4 between the walls of the casing and oven chamber must be dispensed with in employing a rotary type of cleaner in the channel 4 for obvious reasons, it is necessary, in the use of a rotary cleaner, and in order to prevent such objections, to provide a cleaner which, in addition to its function as a cleaner, will also serve as an effective support for the oven chamber 7. My invention is therefore especially designed to perform this double function.

Mounted for rotary or oscillating movements in the chamber 4 between the cylinders and in the space between the walls 9 and 10 is my improved soot cleaner 11. This is of U-form comprising a pair of parallel scraper arms 12 and 13 and a cross rod or arm 14 connecting said arms 12 and 13 at the rear ends thereof. The parts 12, 13 and 14 are preferably formed from a single continuous piece of metal, such as a rod, which may be of round or any other suitable cross sectional form. The cross bar 14 is welded or otherwise suitably fastened at a point intermediate of its length to a shaft 15 which is journaled in bearing openings in the walls 9 and 10 in the line of the axis of the oven and projects outwardly at one end and is provided with an operating crank 16 by means of which the scraper 11 may be rotated or oscillated.

The scraper arms 12 and 13 are, in accordance with my invention, each provided with scraper projections 17 alternately offset in opposite directions, that is, inwardly and outwardly, which projections, in the rotations or oscillations of the scraper, are adapted to bear on the opposed surfaces of the drum walls 2 and 3 to scrape off the accumulated soot deposited thereon. This soot may be allowed to drop back into the stove with which the oven is connected or may be drawn out from the stove pipe into the open atmosphere at periods desired. For the purpose of giving stable support to the scraper and its actuating shaft 15, the walls 9 and 10 are, as shown, preferably provided with dished bearing offsets 18, and the shaft is provided with collars or projections 19 welded thereto or suitably formed thereon to limit its sliding movement in either direction and prevent its displacement and to properly guide it in its rotations.

Since the cleaner is revolvably mounted in the oven and has no projecting parts, except the short crank handle 16, it will be evident that this clean-

er permits the stove on which the oven is placed to be set closer to the wall than a cleaner which must be reciprocated in its cleaning action, and therefore drawn more or less outwardly from the oven, thus reducing the amount of room floor space occupied by the stove. Also it will be observed that the cleaner may be completely revolved, or oscillated back and forth, or rotated intermittently in a single direction by motions imparted to the crank handle. The cleaner may, in fact, be completely revolved by merely striking the crank several times with the hand or another object until it is turned to a desired degree for a cleaning action. This avoids the necessity of gripping the crank handle, which becomes extremely hot, in the unprotected hand while performing a cleaning action. By the provision of the cleaner arms with the offset 17 provision is made for adequately cleaning the opposed surfaces of both drum walls 2 and 3, while at the same time the offsets give increased strength to the cleaner arms to reinforce said arms against distortion under the high heat of the products of combustion circulating in the channel 4. It is the general practice to manufacture pipe ovens of this character of very light sheet iron which is easily dented, and, in case an oven equipped with this cleaner does become dented or warped, the cleaner will still remain serviceable, as the novel offset construction of the cleaner arms or blades will allow the offsets under flexion of the long rod-like cleaner arms to pass over the dented or warped wall portion so that adequate cleaning movements can be made. It will, of course, be understood that the concavo-convex offset bearing portions 18 provide strength and a longer bearing surface for the shaft 15 than would be possible if the walls at this point were straight and parallel.

As stated, shaft 15 is journaled in the dished portions of the rear walls of both the casing and oven. It thus serves not only as a driving element for rotating the cleaner but as a support for the rear end of the oven to prevent the oven from sagging and buckling the wall 8a. It will be observed also that as the series of offsets 17 of the arms 12 and 13 project alternately in opposite directions these offsets contact at all times with the annular body walls of both the casing and oven and simultaneously clean both walls while assisting also to support the weight of the oven and its contents.

From the foregoing description, the construc-

tion, mode of operation and the advantages of my improved stove pipe oven cleaner will be readily understood without a further and extended description, and it will be understood that, while the invention is herein shown in its preferred embodiment, changes in the form, arrangement and details of construction of the parts of the cleaner may be made within the scope of the appended claims without departing from the spirit or sacrificing any of the advantages of the invention.

What I claim is:

1. In a stove pipe oven having spaced outer and inner annular walls forming an outer casing, an inner oven chamber and an annular heat circulating member therebetween, and spaced end walls closing said annular walls respectively at one end of the oven, said end walls having bearing portions offset in opposite directions, a U-shaped rotary scraper embodying scraper arms mounted for movement about the heat circulating chamber and a cross portion connecting said arms and disposed in the space between said end walls, each of said arms being provided with a plurality of crank-like stiffening and scraper offsets projecting therefrom alternately in opposite directions, and in scraping and supporting engagement with both the annular walls of the casing and oven chamber at a plurality of points in the length thereof, and a shaft connected to said cross portion of the scraper and journaled upon said end walls so as to form a support for said end of the oven chamber and provided with an operating crank.

2. In a stove pipe oven having spaced outer and inner annular walls forming an outer casing, an inner oven chamber and an annular heat circulating chamber therebetween, and spaced end walls closing said annular walls respectively at one end of the oven, said end walls having bearing portions offset in opposite directions, a rotary scraper mounted for rotation upon the latter-named end of the oven and having scraper arms movable around the annular chamber for removal of deposits from the annular walls thereof, a scraper operating shaft carrying said scraper and journaled in said offset bearing portions of the end walls, so as to form a support for such end of the oven chamber, and abutments on said shaft disposed in the space between the offsets and engageable therewith to prevent longitudinal displacement of the shaft.

GEORGE H. SWEARINGEN.
